US0D1029048S

(12) **United States Design Patent** (10) Patent No.: **US D1,029,048 S**
(45) Date of Patent: ** May 28, 2024

(54) **COMPACTOR**

(71) Applicant: **Kongsilde Industries A/S**, Soroe (DK)

(72) Inventor: **Asger Knudsen**, Soroe (DK)

(73) Assignee: **Kongsilde Industries A/S**, Soroe (DK)

(**) Term: **15 Years**

(21) Appl. No.: **35/515,409**

(22) Filed: **Jul. 6, 2022**

(80) **Hague Agreement Data**

Int. Filing Date: **Jul. 6, 2022**

Int. Reg. No.: **DM/224015**

Int. Reg. Date: **Jul. 6, 2022**

Int. Reg. Pub. Date: **Oct. 21, 2022**

(57) **CLAIM**

The ornamental design for a compactor, as shown and described.

DESCRIPTION

1. Compactor

1.1 : Perspective

1.2 : Front

1.3 : Back

1.4 : Left

1.5: Right

1.6:Top

1.7: Bottom

The features shown in broken lines in the drawings depict environmental subject matter only, and form no part of the claimed designs; in reproductions, the compactor is shown with symbolic long dash-short dash jagged line denoting a break in its length. The appearance of any portion of the article between the break lines forms no part of the claimed design.

1 Claim, 7 Drawing Sheets
